UNITED STATES PATENT OFFICE.

JOHN F. DOOLITTLE, OF FALFURRIAS, TEXAS, ASSIGNOR TO THE CLEVELAND STEEL
TOOL COMPANY, OF CLEVELAND, OHIO, A CORPORATION OF OHIO.

PUNCH.

1,368,327.

Specification of Letters Patent. Patented Feb. 15, 1921.

Application filed January 5, 1920. Serial No. 349,631.

To all whom it may concern:

Be it known that I, JOHN F. DOOLITTLE, a citizen of the United States, residing at Falfurrias, in the county of Brooks and 5 State of Texas, have invented certain new and useful Improvements in Punches, of which the following is a specification.

This invention relates to punches.

The object of the invention is to provide 10 an improved construction for firmly securing a punching or similar tool to the reciprocating shaft, and which arrangement provides relatively large bearing surface between the punching tool and its securing 15 parts, so as to reduce the liability of breakage of the tool which also insures accurate centering of the tool relative to the work; and which enables several tools of different sizes to be securely clamped to the same 20 operating shaft with certainty of accurate centering of all of such tools.

Further objects of the invention are in part obvious and in part will appear more in detail hereinafter.

25 The invention comprises the construction and arrangement of parts hereinafter described and claimed.

In the drawings Figure 1 represents a 30 sectional elevation of one form of the invention; Fig. 2 is a similar view, illustrating a different size of tool and bushing; Fig. 3 is a plan view of a bushing; Fig. 4 is a sectional elevation thereof on the line 4-4, Fig. 3; Fig. 5 is a view similar to 35 Fig. 1, and illustrating another size of coupling nut; and Figs. 6 and 7 are views similar to Fig. 4 and illustrating additional bushings for use with the nut shown in Fig. 5.

40 I illustrates the reciprocating shaft of the punching machine to which is secured the punching tool. Said shaft is threaded at 2 to receive the threads of the coupling nut 3 which is screwed upon the shaft for securing 45 thereto the punch 4. The coupling nut 3 comprises an upper threaded portion for engaging the plunger and a lower seat portion which receives the bushing. In the drawings the punch is illustrated as provided 50 with an operating end 5 for punching holes, but it will of course be understood that the tool may have an operating end portion for setting rivets or performing other operations than punching holes.

55 The end of the shaft or plunger 1 is cut

off square to form an abutment 6 which contacts the end surface of the punch 4. Said punch is clamped against the abutment 6 by the coupling nut and the parts are so arranged as to enable a series of punches of 60 different sizes to be secured to the same shaft. Preferably the arrangement is such that several punches, according to size, may be made from bar stock of different sizes so as to reduce the cost for tool steel. This 65 result is secured by providing for each coupling nut 3 a series of bushings or seat members 7, the bushings shown in Figs. 1, 2 and 4 all being arranged for use with the same coupling nut and being adapted to 70 receive punches of different sizes. The several bushings all have the same external shape. They are frusto-conical, having an outer conical surface 8 tapered on a relatively acute angle, for example an angle of 75 approximately 12° or less, to the axis of the bushing. Other things being equal this angle will be more acute to thereby increase as much as possible the area of the bearing or seating surface between the bushing and 80 coupling nut, which nut has the inner surface of its opening tapered to fit with the outer surface of the bushings. The angle of inclination should not be so small that the parts will wedge together too tightly to 85 be readily freed. This relatively long conical surface avoids abrupt shoulders and distributes the strains over some length of the tool and avoids breakage or snapping of the head of the tool from its body portion. 90

The inner surfaces of the several bushings which receive the tools are alike in form but different in diameter. These seating surfaces, indicated at 9, are also frusto-conical and preferably slope at the 95 same angle as the external bushing surfaces. Each bushing is adapted to receive a single size of tool, the frusto-conical head 10 of the tool being tapered to correspond with the bushing. 100

This arrangement enables a series of different sizes of tools to be used with the same coupling nut and shaft. For example there will be provided four to six more or less bushings externally tapered to fit the coupling nut 3 shown in Fig. 1, each of said bushings receiving a different size of tool. 105

I may also provide a given shaft with a series of coupling nuts, all of which are arranged to thread upon said shaft but which 110

nuts will have central openings of different sizes each adapted to receive a series of different bushings. Fig. 5, for example, shows a coupling nut 3 adapted to receive the bushings illustrated in Figs. 5, 6 and 7, all of which are of the same external size and shape but are smaller than the bushing shown in Fig. 1. These smaller bushings will receive tools of smaller sizes than the 10 first group or series of bushings.

By using a series of coupling nuts and several series of bushings each tool may have a head portion 10 not materially differing in cross section from the body portion of the 15 tool. Therefore, each tool can be constructed from standard bar stock of minimum size thereby reducing the cost.

What I claim is:

1. In combination, a plunger, clamping 20 means detachably secured thereto and provided with an unbroken frusto-conical seat therein, and a punch having an unbroken frusto-conical surface engaging said seat, the taper of said engaging surfaces having 25 the same angle of inclination toward the cutting end of the punch and being uniform throughout.

2. In combination, a plunger, a coupling nut threaded thereon and provided with a 30 frusto-conical opening therein, a bushing seated in said opening and having frusto-conical inner and outer surfaces, and a punch having a frusto-conical surface seated in said bushing, the taper of all of said frusto-conical surfaces having the same angle of inclination toward the cutting end of the punch and being uniform throughout.

3. In combination, a plunger, clamping means detachably secured thereon and pro-

vided with an unbroken frusto-conical seat 40 therein, the inclination of said seat being uniform throughout and making an angle of approximately twelve degrees with the axis of said clamping means, and a punch having an unbroken frusto-conical surface engaging 45 said seat, the angle of inclination of the engaging surface of the punch corresponding to that of said seat, and the taper of said surfaces being in a direction toward the cutting end of the punch.

4. In combination, a plunger, a coupling nut threaded thereto and provided with a frusto-conical opening therein, a bushing seated in said opening and having frusto-conical inner and outer surfaces, and a 50 punch having a frusto-conical surface seated in said bushing, the inclination of all of said frusto-conical surfaces being toward the cutting end of the punch, making an angle of approximately twelve degrees with the axis 60 of said nut and being uniform throughout.

5. In combination, a plunger, a coupling nut threaded thereto and provided with a frusto-conical opening therein, a unitary frusto-conical bushing having inner and 65 outer inclined surfaces and seated in said nut, the engaging surfaces of said nut and bushing having the same and uniform inclination throughout, and a punch having an inclined surface engaging the inner surface 70 of said bushing, the engaging surfaces of said punch and bushing having the same and uniform inclination throughout, all of said surfaces having their taper in a direction toward the cutting end of the punch.

In testimony whereof I affix my signature.

JOHN F. DOOLITTLE.
